UNITED STATES PATENT OFFICE.

JOHN SCHOENBORN, OF CHICAGO, ILLINOIS.

EXTENSION BRACKET.

Application filed April 12, 1922. Serial No. 551,978.

To all whom it may concern:

Be it known that I, JOHN SCHOENBORN, a citizen of the United States, and resident of Chicago, in the county of Cook and State 5 of Illinois, have invented new and useful Improvements in Extension Brackets, of which the following is a specification.

This invention has relation to supporting devices and refers more particularly to exclusive means for supporting lamps, telephones, store fixtures and the like.

The object of my invention is the provision of an improved extension bracket of the so-called lazy-tongs type. A further object 15 is to provide simple and easily operated means for attaching such articles to the support. To this end my invention consists in the combinations hereinafter fully described and illustrated in the appended 20 drawing of which:

Fig. 1 is a side elevation of a structure embodying the invention.

Fig. 2 is a sectional plan-view through part of the structure,

Fig. 3 is a sectional front elevation of the parts shown in Fig. 2,

Fig. 4 is a side elevation of one of said parts.

In the drawing is shown the corner of 30 a table 1, to the overhanging top of which is clamped a pedestal 2 supporting a post 3, and to this post is anchored the lazy tongs arrangement 4, which in turn supports a second post 5, from which a telephone set 35 is shown held suspended. The device as a whole bears sufficient resemblance to such structures of this type as already found on the market, to make an explanation of its operation unnecessary.

There are certain important features 40 about the lazy tongs device which will now be pointed out. The post 3 is a cylindrical tube and it is shown partly in section in order to disclose a slot 3^a, which extends 45 downward from the top of the post. Through this slot projects an arm 6^a of a plunger 6, which arm pivotally supports the first link 4^a of the lazy tongs. The second link 4^b is pivotally hung from a stationary arm 7. The slot 3^a is of sufficient length to permit the plunger 6 to travel the length required for the operation of the lazy tongs. A cap 8 is fitted into the top of the post, partly in order to improve the appearance

thereof, and also because of the dangerously 55 pointed end of the post which would otherwise be left exposed.

The second post 5 is similarly slotted to receive an arm 9^a of a plunger 9, and the last two links of the lazy tongs are in the 60 same manner supported on this arm and on a stationary arm 10. The top and bottom ends of the post are closed by suitable caps 11, 12.

Directly above the cap 12 it is noticed 65 that the post is somewhat reduced in diameter, and that this reduced portion forms a bearing for a clamping member 13, which extends from the post to the telephone stem 14. This clamping member comprises two 70 half-portions 15, 16, see also Fig. 2, which, when combined, resembles a figure 8. In the portion 15 is provided a pair of protruding hooks 15^a, 15^b, which engage relatively alined perforations 16^a, 16^b of the 75 half-member 16. A key 17, similarly made with perforations 17^a, 17^b, is placed on the hooks 15^a, 15^b, for the purpose of tying the clamping member together.

Now it is noticed that the key 17 extends 80 upward a considerable amount, and that a cap 18 of the telephone stand is directly in the path of the top of this key. When the clamping member is put into position around the telephone stem, it is found that 85 the latter sinks in the clamp until the cap 18 strikes the end of the key, thereby locking the latter in position.

I claim—

1. In a telescoping extension bracket, a 90 pair of posts, a lazy tongs bracket operatively combining said posts, a work supporting clamp attachable to one of said posts and to the work to be supported, said clamp made in two separable parts, and a detachable key combining said two parts, said key held in position by the weight of the work 95 supported.

2. In a support, the combination with a 100 table bracket, of a lazy tongs arrangement extending from said bracket, and a clamping device attachable to the end of said arrangement, said device made in two half portions, and an independent key bar attachable to combine said half portions, said 105 bar maintained in position by the article supported by said clamping device.

3. In a support column mountable on a

desk, a second column, a lazy tongs device operatively combining said columns, a two part clamping member attachable to said second column and to an article to be supported, and a key locking said two parts together to hold said member in position, said key held in place on the clamp by the article supported.

4. In a lazy-tongs support, in combination, a pair of tubular posts having each a slot extending downward from the top and facing each other, plungers slideable in said tubes and having arms projecting through said slots for connection with the lazy tongs of the support, and clamping means engaging one of said posts and the article supported, said means comprising a pair of members one of which is provided with hooks projectable through perforations in the other, and a key-bar engaging said hooks

to clamp said members together, said bar held in place by the article supported.

5. The combination with a table bracket, of a lazy tongs arrangement extending from said bracket and terminating in a cylindrical column, a pair of clamping members combining to form a numeral 8, one eye of which encompasses said column and the other engaging the article supported, one member having hooks between the eye portions, which hooks extend through perforations of the other member, and a key engaging said hooks to draw the said members around the column and the article supported, the key maintained in position by said article.

In testimony whereof, I have hereunto affixed my signature.

JOHN SCHOENBORN.
